Edwin Bell,
INVENTOR, BY
Charles H. Woodward
Atty.

UNITED STATES PATENT OFFICE.

EDWIN BELL, OF ST. PAUL, MINNESOTA.

PROTECTING ROAD-BEDS OF RAILWAYS.

SPECIFICATION forming part of Letters Patent No. 432,969, dated July 29, 1890.

Application filed May 13, 1890. Serial No. 351,705. (No model.)

To all whom it may concern:

Be it known that I, EDWIN BELL, a citizen of the United States, residing at St. Paul, in the county of Ramsey and State of Minnesota, have invented certain new and useful Improvements in Protecting the Road-Beds of Railways, of which the following is a specification.

Great damage frequently results to the road-beds of railways from the action of water during heavy rains or melting snow, and to protect the road-beds from such damage is the object of my invention, which consists of "mats" or brush-wood embedded beneath the ends of the ties to form barriers to prevent the water from undermining the road-bed, as hereinafter shown and described, and specifically pointed out in the claims.

In the drawings, Figure 1 is a cross-sectional view of a railway-track and a portion of the land on each side with my improvement arranged in connection therewith. Fig. 2 is a plan view of the same. Fig. 3 is a perspective view of one of the brush-mats detached. Fig. 4 represents a detail similar to Fig. 1, illustrating a slight modification in the adaptation of the invention.

A' A² represent the rails, B the ties, and D the road-bed, of a railway-track of the ordinary construction. The mats, as before mentioned, are constructed of pieces of brush-wood of any kind, but will preferably be of willow, which withstands the action of the water and resists decay better than most wood, besides being generally easily obtainable and of the proper size.

For convenience of handling the mats are generally constructed as follows: Two strips a' a² are laid upon the ground convenient to the place where a plentiful supply of brush of the proper size can be obtained, and a series of staples driven into them about four feet apart, or holes formed through them at the same distances apart, if preferred. Through these staples or holes the binding-wires are to be passed and running up through the mass of the brush, which is laid across the strips and pressed solidly together either by levers or by other suitable means.

The mats will generally be constructed

about sixteen inches thick, three or four feet wide, (the width being the lengths of the pieces of brush,) and from twelve to twenty feet long.

After the mats are as thick as required, additional strips a³ a⁴ will be placed along the top outer edges and bound fast by the binding-wire, thus forming a compact mass that can be readily transported to any required distance.

In applying my invention the earth is excavated from beneath the ends of the ties B to a depth of about sixteen inches, more or less, according to the nature of the soil, and the brush-mats laid in these excavations with the upper binding-strips a³ a⁴ beneath and in contact with the outer ends of the ties, as shown, and the earth tamped closely against their ends. A layer of earth is then placed over the mats to protect them from fire, and in locations where a very heavy overflow of water is liable to occur "ballast" of stones or sand-bags may be laid upon the outer ends of the mats to prevent them being washed out, the inner ends being held down by the ties. Diagonal filling-pieces E will be fastened between the ties B above the strips a' to prevent the water washing in beneath the rails and undermining the ties.

The size of the brush-wood mats may be varied to suit the conditions or the location of the road-bed. These mats will be required only in locations where there is danger from freshets or overflows from whatever cause.

If required, hydraulic cement may be run in around the sections of boards E as a "packing," to prevent the passage of the water. The diagonal filling-strips E also perform an important function in strengthening the rails and preventing them from spreading, as they bear against the outer edges of the rails and resist any pressure which may be exerted against the rails from their inside edges.

In locations where the railway runs upon the surface of the rock, in cañons, rock-cuts, &c., and where the ballast is the only loose portion of the road-bed, the brush-wood mats or filling may not be of sufficient depth to bear the weight of the ties, track, and the trains. Under such conditions a supporting-

timber F may be inserted beneath the ties (see Fig. 4) inside the brush-wood mats to carry a portion of the load.

The water in flowing over the road-bed will 5 deposit within the interstices of the brush-wood forming the mats, sand and other sediment, which soon fills them, and thereafter water flowing over them will not affect them in any manner, but on the contrary every increase of the overflow more firmly fixes them in position by depositing the sediment more closely within the mats. The sand deposit also preserves the brush-wood from decay, so that when properly laid they last for many 15 years without renewal.

Having thus described my invention, what I claim as new is—

1. A protection for the road-beds of railways from the action of water, consisting of 20 brush-wood embedded partially beneath the ends of the ties, substantially as and for the purpose set forth.

2. A protection for the road-beds of railways, consisting of mats formed of brush-

wood and embedded partially beneath the 25 ends of the ties, substantially as and for the purpose set forth.

3. The combination, with the road-beds of railways, of mats of brush-wood embedded beneath the ends of the ties to form protectors 30 for the road-beds against the action of water, substantially as and for the purpose set forth.

4. In a protector for the road-beds of railways, mats of brush-wood formed with binding-strips a' a^2 a^3 a^4 along their edges, and 35 adapted to be embedded with their ends beneath the ends of the ties, and water-guards E, inserted between the ties and above said mats, substantially as and for the purpose set forth.

In testimony whereof I have hereunto set my hand, in the presence of two subscribing witnesses.

EDWIN BELL.
